MARKING ROLL WITH METAL PLATES AND CUSHION

Filed July 28, 1930

UNITED STATES PATENT OFFICE

HERMAN G. WEBER, OF PHILADELPHIA, PENNSYLVANIA

MARKING ROLL WITH METAL PLATES AND CUSHION

Application filed July 28, 1930. Serial No. 471,202.

This invention relates to a marking device and more particularly to such a device having special utility in a paper-making machine for imparting water marks or other designs to the paper or other fibrous web as it moves through the machine.

Various grades and qualities of paper are required in the industry and, accordingly, it is advisable to mark the papers to indicate the quality thereof and the company by which it is manufactured. This result is generally accomplished by means of rolls having surfaces with designs thereon which are impressed on the paper, in present practice, usually after it leaves the forming part of the machine and before it reaches the calender rolls.

As will be appreciated, the designs on said surfaces wear out after a time, or in some instances, it may be desired to change the grade of paper made in the machine, in which event it becomes necessary to remove the marking rolls. If the marking faces of the rolls are worn out, the rolls are usually dismantled and new or renewed marking faces applied thereto, as required by economical practice.

Marking rolls heretofore generally employed for this purpose comprise either the stereotype form in which stereotype marking plates are rigidly secured to a supporting roll or shaft, or the engraved rubber form. The latter type employs marking faces of hard gum secured to the supporting roll by a layer of soft, endless rubber bands in turn secured to the shaft, or by intermediate layers of soft and hard rubber vulcanized together and fixed to the supporting roll or shaft.

The stereotype form of marking surfaces when forced against the fibrous web produces a tendency for the types to cut therethrough, and, hence, it is necessary to dull the faces of the type by wrapping the roll with one or a number of layers of fabric. This material, however, readily wears out and must be replaced by a new wrapping, all of which involves labor, time, and expense. In addition, when the stereotypes wear out or the quality of paper produced by the machine is changed, considerable time and dif-

ficulty is experienced in replacing the rolls in the machine by other rolls, dismantling the rolls if worn, and in renewing and reconstructing the rolls. Similar problems are presented in the engraved gum surface rolls, especially in regard to the removal and replacement of worn marking surfaces.

I have now constructed a stereotype form of marking roll which is singularly free from the above objections in that it has a rather low initial cost, has a readily removable marking surface permitting it to be quickly constructed and dismantled, and a low operating cost.

It is, accordingly, an object of my invention to provide a stereotype marking roll so constructed as to obviate the necessity of wrapping the marking surface thereof.

It is a further important object of my invention to provide a marking roll having a marking surface which can be quickly and easily mounted on and removed from its supporting roll or shaft.

It is a further important object of my invention to provide a marking roll which is relatively cheap, easy to construct, and renew, and has a high efficiency in use.

Other and further important objects of my invention will become apparent from the following description and appended claims.

Referring now to the drawing which discloses a preferred form of my invention:

Figure 1 is a side elevational view of my improved marking roll with parts in section and parts broken away.

Figure 2 is a sectional view taken on line II—II of Figure 1.

The marking roll of this invention is indicated generally by the reference numeral 1 and comprises a core or supporting roll 2, which is made hollow to decrease the total weight thereof. Journal extensions 3 are pressed into each end 4 of said core 2, and are maintained securely in position therein by pins or keys 5.

The entire periphery 6 of said core or support 2 is surrounded by a resilient cushioning sleeve 7 of cork, natural or "synthetic" rubber or the like, cemented or otherwise firmly anchored to the core 2. While the

sleeve 7 is herein shown as comprising a single sleeve of the length of core 2, it may well comprise a plurality of smaller sleeves preferably slightly spaced apart and united to the core to provide a cushioning layer about the periphery of said core.

Said cushioning sleeve 7 is in turn surrounded by a layer 8, made up of a plurality of steel sleeves 9 of such diameter as to fit over and snugly hug about said cushioning sleeve 7. The size of said steel sleeves 9 may be varied as desired, but are preferably of a width of from 6 to 12 inches and a wall thickness of about 1 to 2 inches.

The steel sleeves 9 form a support for the marking surface 10 of the roll, which is composed of a plurality of thin sleeves 11 of brass, steel, type metal or some similar metal which can be readily etched or engraved to provide a stereotype marking sleeve. Said sleeves 11 are secured to the steel sleeves 9 by means of small screws 12 having countersunk heads 13.

The outer surface of each marking sleeve 11 carries an etched or engraved design 14 either complete in itself or forming part of a single design 15 of the entire roll marking surface. In either event, in order that the required design be properly impressed on the paper or other fibrous web, it is necessary that said sleeves be properly adjusted with relation to each other and securely retained in such adjusted relationship. This result is accomplished by providing the abutting ends of the steel sleeves 9 about the periphery thereof with cooperating slots or recesses 16 and placing small pins 17 in said slots or recesses. These small pins, thereby effectively prevent relative movement of said steel sleeves 9 and, hence, the marking sleeves 11.

The particular wall thickness of the marking sleeves 11 is, of course, a matter of design and expediency but satisfactory results are obtained with sleeves $\frac{1}{2}$ inch in thickness.

The ends 4 of the core 2 are cut away from the periphery of the core to a point spaced inwardly a distance therefrom to provide in each end 4 a circular notch or recess 18. The walls 19 of said recesses limit the length of the sleeve 7, layer 8, and marking surface 9. A steel collar or ring 20 is located in each recess, and lies flush with the end of said sleeve 7, layer 8, and marking surface 10. Said collars 20 are rigidly secured to the ends of core 2 and the outermost of the steel sleeves 9 by screws 21 threaded thereinto to thereby retain the steel sleeves 9 and marking sleeves 11 on the supporting core 2, and preventing shifting of said sleeves 9.

While I have disclosed each marking sleeve as having the same length as a retaining or supporting steel sleeve 9, it is to be understood that this is not a structural limitation, as the ratio between the length of the two sleeves may vary at will. Similarly, it is not

necessary that the entire length of the marking roll 2 be provided with a marking surface for the marking sleeves 11 may cover any portion of the roll that is desired or expedient.

The building up and dismantling of a roll of this type, as will be appreciated from its structure, can be quickly and easily accomplished. To build up or construct the roll, it is merely necessary to slip the cushioning sleeve onto the core 2 and fasten it thereto, secure the marking sleeves or stereotypes 11 to the steel sleeves 9 and slip the combined sleeves over the cushioning sleeve 7 and fix the collars 20 in place. The dismantling of the roll can be effected as easily and readily by reversing the above procedure. It is, therefore, apparent that if it is desired to change the marking surface of a roll for any reason, that the same can be quickly and readily done with but little labor. Moreover, since the marking sleeves are the only part of the roll requiring replacement, it is only necessary to carry a large supply of these elements in stock.

When the roll is in operation, the layer 7 cushions the marking surface of the core 2 providing for a springy or cushioned impact of the marking surface against the paper web, thus preventing said marking surface from cutting the web. It is, therefore, not necessary in this construction to wrap the marking roll with fabric as is the practice with other forms of stereotype marking rolls.

The marking roll above described can be used in any type of paper-making machine in conjunction with either the press or drying rolls thereof, and may be used to impart either a water mark in paper or an embossed design in cardboard. Moreover, if desired, this roll may even be employed for printing a design on the paper web.

When this roll is employed to mark paper webs of relatively great width, it will be necessary to give the marking surface thereof a slight crown at the center thereof in order to compensate for the "springing" of the heavy roll over which the paper web moves while contacting the marking roll.

It can, therefore, be appreciated that I have constructed a roll having great utility in the marking of fibrous material, and which can be quickly constructed and dismantled, and has a very high efficiency of operation.

Various details of my structure may be varied without departing from the spirit of my invention, and accordingly, I do not intend to be limited in the patent granted except as necessitated by the prior art.

I claim as my invention:

1. A marking roll comprising a supporting shaft, a layer of resilient material secured to the periphery of said shaft, detachable metallic sleeves about said layer of resilient material and of such diameter as to

snugly fit about said layer, stereotypes secured to said sleeves, and means for detachably maintaining said sleeves on said shaft.

2. A marking roll comprising a supporting shaft, a layer of resilient material secured to the periphery of said shaft, metallic sleeves about said layer of resilient material and of such diameter as to snugly fit about said layer, a plurality of stereotype sleeves secured to said metallic sleeves, and means for detachably securing said metallic sleeves on said shaft.

3. A marking roll comprising a supporting shaft, a layer of resilient material secured to the periphery of said shaft, metallic sleeves about said layer of resilient material and of such diameter as to snugly fit about said layer, stereotype sleeves secured to said metallic sleeves, means for preventing relative movement between said metallic sleeves, and means for detachably retaining said metallic sleeves on said shaft.

4. A marking roll comprising a supporting shaft, a layer of resilient material secured to the periphery of said shaft, metallic sleeves about said layer of resilient material and of such diameter as to snugly fit about said layer, a plurality of stereotype sleeves secured to said metallic sleeves, and rings secured to the ends of said shaft and the outermost of said metallic sleeves to detachably maintain said sleeves on said shaft.

5. A watermarking roll comprising a supporting shaft, a layer of resilient material secured to the periphery of said shaft, a plurality of metallic sleeves, about said layer of resilient material and of such diameter as to snugly fit about said layer, means for preventing relative rotation between said metallic sleeves, a plurality of stereotype sleeves secured to said metallic sleeves, and a ring secured to each end of said shaft and the outermost of said metallic sleeves, detachably retaining said sleeves on said supporting shaft.

6. A readily renewable marking surface for water marking rolls comprising a plurality of steel sleeves having stereotype sleeves detachably secured to the outer surfaces thereof, and means between said steel sleeves to prevent relative movement therebetween.

In testimony whereof I have hereunto subscribed my name at Chicago, Cook County, Illinois.

HERMAN G. WEBER.
